UNITED STATES PATENT OFFICE.

CHARLES A. HULTQUIST, OF LOS ANGELES, CALIFORNIA.

DRILLING-MACHINE.

1,221,862.

Specification of Letters Patent.

Patented Apr. 10, 1917.

Application filed December 2, 1916. Serial No. 134,726.

To all whom it may concern:

Be it known that I, CHARLES A. HULTQUIST, a citizen of the United States, residing at Los Angeles, in the county of Los Angeles and State of California, have invented a new and useful Drilling-Machine, of which the following is a specification.

This invention pertains to devices of the character designed to cause turning of the 10 drill steel of pneumatic tools such, for instance, as stoping machines and an object of the invention is to effect such turning of the drill by mechanism of maximum simplicity and effectiveness.

15 Another object is to produce mechanism of this character in which the power impulse for turning the drill will be delivered to the body of the drilling machine to the best advantage and without the use of 20 gear wheels.

Other objects and advantages will appear in the subjoined detail description.

The accompanying drawings illustrate the invention:

25 Fig. 1 is a side elevation of a drilling machine equipped with the invention, portions of the drill, feed cylinder and handle being broken away to contract the view.

30 Fig. 2 is an elevation mainly in section on the irregular line indicated by x^2-x^2 , Fig. 3.

Fig. 3 is an enlarged plan section on line indicated by x^3-x^3 , Fig. 1.

35 Fig. 4 is an elevation partly in section on line indicated by x^4-x^4 , Fig. 2.

Fig. 5 is a fragmental sectional elevation on the irregular line indicated by x^5-x^5 , Fig. 4.

40 There is provided a cylinder 1 having at one end thereof a chuck 2 to hold a drill steel 3 in a manner well understood in the art. The opposite end of the cylinder 1 is provided with a feed cylinder 4 having therein a feed piston 5 operated by compressed fluid so as to press the drill against the material to be drilled as is well understood in the art. The type of drilling machine illustrated in Fig. 1 is generally termed a stoping machine but the features 45 of the invention hereinafter to be described may be used in connection with other types of drilling machines.

50 The cylinder 1 and the feed cylinder 4 constitute the body of the drilling machine and means are provided to turn or oscillate said body about its longitudinal axis and

said means will now be described. The feed cylinder 4, or other suitable portion of the body, is journaled in bushings 6 of bearings 7 which are formed at opposite sides of a 60 transversely disposed member comprising a semicylindrical casing or jacket 8 and cylinders 9, 10 arranged parallel with one another. The cylinders 9, 10 are provided with intake ports 11, 12 respectively which 65 communicate with a valve device 13 of any suitable type capable of being operated by compressed fluid so as to alternatively admit operating fluid to the ports 11, 12. The air supply pipe for the valve device 13 is 70 indicated at 14.

The cylinders 9, 10 are provided with pistons 15, 16 respectively adapted to be forced inward by the air admitted to the cylinders by the valve device 13, and said cylinders 75 are connected by pins 17 to piston rods 18, 19 respectively which in turn are pivoted at 20 to radial arms 21 of a collar 22 that is tightly clamped by means of a bolt 23 onto the feed cylinder 4, there being a slot 24 in 80 the collar so as to allow the bolt 23 to be drawn up to produce the clamping action of the collar. Equivalent means could be used to fasten the collar 22 in place.

The collar 22 is of just sufficient thickness 85 to fit between the adjacent ends of the bearings 7 so as to form a thrust collar or shoulder on the cylinder 4 between said bearings and thereby prevent movement of the casing 8 and cylinders 9, 10 lengthwise of the feed 90 cylinder 4.

The mechanism for producing blows on the drill steel 3 is not shown and described in detail as said mechanism may be of any suitable construction and is well understood 95 in the art and is not a part of this invention.

The throttle valve handle is indicated at 25 and fastened to the cylinders 9, 10 is a handle 26. In practice to operate the drilling machine, the operator will grasp the 100 handle 26 to steady the machine and to hold the cylinders 9, 10 stationary and will turn on the compressed air by operating the throttle valve handle 25 in a manner well understood in the art so as to produce blows 105 on the drill steel 3 and to produce pressure in the feed cylinder 4 and will open the valve 27 to reciprocate the valve device 13 to admit compressed air alternatively to the cylinders 9, 10 behind the respective pistons 15, 16.

Assuming that the parts are in the posi-

tions shown in Figs. 3 and 5, it is clear that the compressed air will flow from the valve device 13 through the port 11 into the cylinder 9 so as to force the piston 15 on its 5 out stroke so as to turn the collar 22 in the direction of the arrow *a*, Fig. 3, thus to turn the feed cylinder 4 and thereby turn the drill steel 3 to the left in Fig. 1. At the same time the rod 19 moves the piston 10 16 inward.

Then the valve device 13 will be operated in a manner well understood in the art to cut off the air supply from the port 11 and to supply air through the port 12 to the 15 cylinder 10 to drive the piston 16 outward and thereby turn the collar 22 in a direction opposite to the arrow *a* to thereby turn the drill steel to the right in Fig. 1 and return the piston 15 to the position shown in solid 20 lines in Fig. 3.

The valve device 13 thus continues to alternatively admit air to the cylinders 9, 10 so as to oscillate the feed cylinder 4, the 25 oscillations of said feed cylinder being transmitted to the drill steel 3 so as to produce the desired changes in the relation of its cutting edges to the surfaces acted on by the drill steel.

I am aware that pistons have been used in 30 connection with spur gearing to turn the drill steel in prior devices, but it is noted that by the herein before described construction gear wheels are dispensed with, and, since it is well known that there is con-

siderable wear to gear wheels, it is clear 35 that the described construction will outwear those devices employing gear wheels.

I claim:

1. The combination with the body of a drilling machine, of a collar fastened to said body, a casing surrounding said collar and journaling the body of the drilling machine, a pair of cylinders connected to the casing, a valve device to admit operating fluid alternatively to the cylinders, and pistons in 45 the cylinders connected with said collar.

2. The combination with the body of a drilling machine, of a casing provided with bearings to journal said body, a collar fastened to said body and interposed between 50 the adjacent ends of said bearings, cylinders connected with the casing, pistons in the cylinders, and rods pivoted to the pistons and to the collar to operate said collar.

3. The combination with the cylinder of 55 a drilling machine, of a collar fastened to said cylinder, bearings to journal said cylinder, cylinders connected with said bearings, pistons in the cylinders connected with the collar, and a valve device to admit an 60 operating fluid to the last named cylinders alternatively.

Signed at Los Angeles, California, this 24th day of November 1916.

CHARLES A. HULTQUIST.
